UNITED STATES PATENT OFFICE.

BENJAMIN F. MAYO, OF SALEM, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LAST-PULLING MACHINE.

1,274,738.

Specification of Letters Patent. Patented Aug. 6, 1918.

Application filed September 16, 1916. Serial No. 120,510.

To all whom it may concern:

Be it known that I, BENJAMIN F. MAYO, a citizen of the United States, residing at Salem, in the county of Essex and State of Massachusetts, have invented certain Improvements in Last-Pulling Machines, of which the following description, in connection with the accompanying drawings, is a specification, like reference characters on the drawings indicating like parts in the several figures.

This invention relates to machines for separating shoes and lasts and is more particularly concerned with means to facilitate the separation of the shoe and last by stretching the shoe on its last and by relatively positioning the shoe and last best to facilitate the separation of these members.

In a type of last pulling machine to which the present invention may be advantageously applied, the shoe is inverted and held with its bottom in substantially horizontal position while the last is pulled from the shoe through instrumentalities which pull it diagonally downward and rearward, the line of pull having one component substantially perpendicular to the normal (substantially horizontal) plane of the shoe bottom with a second and increasing rearward component of movement in the direction of the heel end of the shoe.

In the first part of the relative separating movement between the shoe and last, the last heel is pulled downwardly until the bottom of its heel substantially clears the rear edge of the shoe counter, from which point the last is moved downwardly with a very substantially increased rearward component of movement to separate the last from the shoe.

Last pulling machines illustrative of the described type are shown and fully described in my co-pending application filed Nov. 2, 1914, Ser. No. 869,824, and in United States Letters Patent No. 1,203,571 granted Nov. 7, 1916 upon the application of John T. Benjamin, filed Mar. 10, 1915, Ser. No. 13,385. For the purpose of illustrating the present invention I have shown it as embodied in the commercial type of machine such as shown in United States Letters Patent No.

1,203,571, and while it is employed with particular advantage in the general type of last pulling machine previously described, it is recognized that it may be embodied in and coöperate with other forms of last and shoe separating instrumentalities.

The shoe and last separation, from the standpoint of strain upon the shoe parts, may be divided into two stages. The first and more severe stage of strain includes that portion of the relative separating movement in which the last heel and shoe counter have relative movement substantially perpendicular to the initial plane of the shoe bottom until the lower edge of the last heel substantially clears the upper edge of the shoe counter. The second and lesser stage of strain includes relative movement of the last and shoe from the position at the described end of the first stage diagonally downward and rearward to pull the forepart of the last from within the forepart of the shoe.

It is the purpose of the present invention to provide means operative to reduce the strains upon the shoe parts during these stages of strain and separation without slowing down the normal speed of operation of the machine and, in fact, effective to "speed up" the machine by reducing the resistance to separation.

Accordingly, one feature of the present invention consists in the combination with means for holding a last, means to engage and grip a shoe seated over the last and mechanism for effecting relative movement of said shoe gripping and last holding means in directions to separate the shoe and last, of means operative in timed relation to stretch the shoe transversely on the last during such relative separating movement, and, preferably, during the period in which the last heel moves substantially to clear the shoe counter. Obviously, the stretching of the upper materials is of substantial assistance in easing the heel end of the last out of the heel end of the shoe and in stretching the counter and forepart of the shoe upper while the last moves slightly rearwardly and downwardly.

A further feature of the invention consists in combination with shoe and last holding

means and mechanism for effecting relative movement of the shoe and last holding means to separate the shoe and last, of means operative relatively to incline the shoe and last 5 transversely of the shoe and last and to maintain such relative inclination for a determinate period during the relative separating movement of the shoe and last.

Right and left lasts have their inner side 10 faces substantially flat with the instep portions undercut, and have their outer side faces convex or "full". As previously practised, the shoe has been supported with its bottom substantially horizontal and the last 15 has been moved diagonally rearward during the second stage of separation, this rearward movement having one component substantially perpendicular to the plane of the shoe bottom. Under these conditions the outer 20 side face of the last exerted substantial lateral pressure against the outer (convex) side face of the shoe upper as it was pulled from the shoe, while, owing to the flat and undercut surface of the inner side face of 25 the last, only slight lateral pressure was exerted against the inner side face of the shoe.

The present invention effects a more equal distribution of pressure against the sides of the shoe upper and prevents excessive lateral 30 strain by providing means operative to incline the shoe transversely at a determinate angle to its normal plane, pressing the inner side face of the shoe against the inner side face of the last so that heelward movement 35 of the last with a component substantially perpendicular to the normal plane of the shoe bottom will cause the last to recede from the outer side face of the shoe upper in the direction of the inner side face of the 40 shoe and with lateral pressure against the inner side of the shoe upper. The inclination is preferably such that the lateral pressure against the opposite side faces of the shoe upper, as the last is moved from the 45 shoe during the second stage of separation, is substantially equalized and the unlaced edges of the upper will yield outwardly in response to such pressure without injuring the shoe.

50 The angle at which the shoe is inclined will be reversed for right and left shoes since the inner side faces of rights and lefts are at opposite sides. Accordingly, a further and related feature of my invention 55 consists in combination with shoe and last holding means and mechanism for effecting relative separating movement, of means operative relatively to incline the shoe and last transversely of the shoe and last and at 60 maintained angles of inclination reversed in alternation during successive cycles of the machine.

A related feature of the invention consists in means to indicate to the machine operator the conditioning of the machine for

inclination for right or left shoes. In a large number of factories, the shoes whose lasts are to be pulled, are routed to the operator in pairs so that an alternating right and left inclining action adapts the machine 70 to this practice. If the shoes run in rights or lefts, the operator has only to treadle the machine for an empty cycle, between successive right or left shoes, as the case may be. This does not mean a loss of time for 75 the "empty" cycle can be made to occur while disposing of one pulled last and shoe and reaching for the next shoe and last to be operated upon. The indicator is a safeguard to insure presentation of the proper 80 shoe and of the "rights" and "lefts" in proper order.

These, and other features and advantages are more fully described in the following detailed specification when read in connection with the accompanying drawings, in 85 which—

Figure 1 is a view in side elevation, partly in section, showing a last pulling machine of the Benjamin type embodying the features 90 of the present invention.

Fig. 2 is a fragmentary view in rear elevation of the indicator, cam, and rocking lever and crank for the shoe gripping head; 95

Fig. 3 is a detail of the indicator;

Fig. 4 is an enlarged vertical section on the line 4—4 of Fig. 5, showing a right shoe held in inclined position for the withdrawal of the last during the second stage of operation;

Fig. 5 shows in side elevation, diagrammatically, the position of the shoe, last, and last pulling members with the shoe and last in the relation shown in Fig. 4; and

Fig. 6 is a tabulated plot of the peripheral cam groove controlling the operation of the rocking devices for the gripping head and the indicator.

The parts and operation of the Benjamin last pulling machine shown herein need only 110 be described briefly since the specific construction forms no part of the present invention. Briefly, the machine comprises a hollow standard in which is journaled a shaft 4, driven through a pulley 6 which receives power from a belt or other driving medium, the pulley being loose on the shaft and a one cycle clutch mechanism being employed to couple the pulley to the shaft and to rotate the shaft through a half revolution forming, in the present instance, a complete work cycle and automatically to unclutch the pulley and arrest the further movement of the shaft at the end of said cycle. The clutch mechanism is operated to 115 start the revolution of the shaft 2 through a treadle 22 mounted at the base of the standard, the shaft 2 having mounted thereon within the hollow standard, a worm 42 meshing with a worm gear 40 mounted upon 120 125 130

a cam shaft 38 extending transversely of the machine within the standard and carrying a cam wheel 36. One half revolution of this cam wheel constitutes a machine 5 cycle, and through this cam wheel mechanism is operated to pull the last from the shoe and to grip the shoe while the last is pulled therefrom.

The periphery of the cam wheel 36 at 10 one edge and at diametrically opposite points is formed with low parts or depressions 62 in which a roller on the lower end of a bell crank lever 64 is arranged to drop and to be held in the position of rest of the 15 machine parts. The upper end of the bell crank lever 64 when the cam wheel 36 is rotated, and the lower end of the bell crank is raised by contact with the high part of the cam periphery operates a plunger to close 20 oppositely disposed shoe counter and heel gripping blocks (Fig. 4) to grip the heel and counter of a shoe between them and to hold the shoe in position during the last pulling operation and while the lower end 25 of the bell crank remains upon the high part of the cam wheel periphery. The fore-part of the shoe may be supported by a swinging saddle 178 forming a toe rest and the opposite sides of the shank may be engaged 30 by welt crease blades 106. The toe support, welt crease blades and counter and heel grippers with their operating connections are carried by a head 200.

As previously constructed, this head has 35 been extended over and rigidly secured to the top of the hollow standard. According to the present invention, however, the head terminates adjacent to the forward edge of the standard and is provided with a shaft 40 202 mounted for rocking motion in a journal 204 secured to the top of the standard. The coiled springs 70 which are connected to the heel and counter block operating mechanism at their forward ends, have their 45 rearward ends anchored to posts upstanding from the journal 204, the apertures in the head 200 through which the springs extend, being elongated sufficiently to permit bodily swinging movement of the springs during 50 rocking motion of the head.

The contact face at the upper end of bell crank lever 64 which engages with the rear end of a plunger 72 operating the gripper blocks, is of sufficient size to remain in contact 55 with the end of the plunger when the head is oscillated and, is preferably provided with a laterally extended contact face for this purpose. The rear end of the plunger may be provided with a suitable anti-friction contact member. The head of the 60 standard and the journal 204 are appropriately slotted, as shown, to permit the upper end of the bell crank lever 64 to extend therethrough and to swing forwardly and 65 backwardly. The springs 70 are operative

normally to retract the gripper blocks and to move the plunger 72 to engage its rear end with the end of the bell crank lever 64 to hold the lower end of the bell crank in contact with the peripheral edge of cam 36. 70

The rear end of the rock shaft 202 is extended beyond the rear of the standard and is provided with a crank arm 206, preferably bifurcated to receive the upper end of a 75 rocking lever 208 pivoted at its lower end on the standard and intermediate of its ends carrying a roll 209 operated through the cam 36 to rock the lever 208, crank arm 206 and rock shaft 202. The upper end of the lever 208 has an elongated slot through which a 80 connecting pivot pin extends. Adjacent to the crank arm 206, a yoke 210 is pivotally mounted at its lower end on the rear of the standard and has its upper end formed as an indicator finger 212 co-operating with an 85 indicator plate 214 bolted to the face of the journal 204. The lower end of the yoke 210 is provided with a bent arm 216 extending downwardly and inwardly therefrom and having a roll 217 at its lower end, also co-operating with the cam wheel 36, as later described, to swing the yoke and position the finger 212 relatively to the plate 214 to indicate at the end of one cycle the condition 90 of the machine for operation during the next cycle upon right or left shoes, as the case may be.

Before being positioned between the gripping blocks, a last with a shoe thereon, is 100 mounted on the heel pin 142 of a carrier arm 144, the front end 194 of which forms a handle. The rear end is pivoted at 145 to the upper end of one arm 146 of a bell crank lever supported by and pivotally attached to the upper end of a plunger 150. The 105 upper end of a rod 154 is pivotally attached to the end of the other arm 152 of the bell crank lever, and has its lower end guided through an extension from the standard. A coiled spring 158 encircles the rod between 110 the bell-crank lever and standard extension and is compressed by downward movement of the arm 152 of the bell crank lever, and operates to swing the arm 146 rearwardly when the last heel clears the shoe counter 115 and permits substantial rearward movement of the last.

The last and shoe are positioned on the carrier and the latter is swung upwardly properly to position the heel end of the shoe between the gripping blocks. The treadle 22 is then operated, throwing in the clutch and rotating the cam shaft through a half revolution. The bell crank lever 64 will operate the plunger 72 moving the gripper blocks to clamp 125 and hold the shoe during the period of last pulling. The plunger 150 is moved downwardly in turn to pull the bell crank lever 146, 152, carrier 144 and the last downwardly and rearwardly, by a bar 172 having its 130

upper end bifurcated to embrace the hub of the cam 36 and having a roll offset therefrom and arranged to be engaged by oppositely disposed wiper cams on one side face of the 5 cam wheel 36 to move the bar downwardly and to permit it to return upwardly during each machine cycle. The lower end of bar 172 is pivoted to a cross bar 166 at a point between its front and rear ends which are 10 pivoted respectively to the lower end of the plunger 150 and to the standard.

The wiper cams, previously referred to, act against the bar 172 in timed relation and after the gripping blocks have been moved 15 to engage and hold the shoe. When the active wiper cam passes beyond the offset roll of the bar 172, a weight 169 returns the bar and its connected parts to their original position, ready for another cycle of operations. As the cam wheel 36 approaches the 20 end of a half revolution (and the end of the machine cycle), the lower end of bell crank lever 64 will drop down in the second low part 62 in the peripheral edge of the cam, 25 permitting the springs 70 to retract the plunger 72 and the gripping blocks to release the shoe.

In accordance with the present invention the cam wheel 36 is provided substantially 30 centrally of its periphery and laterally offset from the path of contact of the end bell crank 64 (see Fig. 2) with a peripheral cam groove 218 into which extend the rolls 217 and 209 on the extension 216 and rocking lever 208 35 respectively. This peripheral cam groove is plotted in Fig. 6 and the rocking, inclining, and stationary or "dwell" sections of each of the two cycles are indicated by appropriate marginal notations.

40 The rolls of the indicator yoke and rocking lever are relatively positioned so that at the end of one cycle, the indicator roll 217 will rest in a section of the cam groove laterally offset from the central line *c-c* of 45 the cam groove to swing the yoke finger 212 to indicate that the next cycle will incline the shoe gripping head for right or left shoes, as the case may be; while the rocking lever roll 209 will be positioned at the beginning 50 of a straight or "dwell" section 220 of the cam groove. This "dwell" is of such length that the rotation of the cam wheel 36 at the beginning of a machine cycle will cause the gripping blocks to engage and 55 hold the shoe before the roll 209 enters into the reversely curved rocking sections 222.

These rocking sections 222 of the cam groove are arranged to impart a complete 60 rocking reciprocation to the gripping head 200 while the last is being pulled substantially to clear the bottom of its heel from the edge of the shoe counter. In operating upon a left shoe, the rocking section 222 will be 65 figured to stop its rocking movement with the shoe gripping head inclined transversely

of the last with the shoe pressed against the inside face of the last which is being pulled downwardly in a line having one component substantially perpendicular to the initial plane of the shoe bottom, the laterally offset 70 straight portion 224 of the groove which follows the rocking bends 222 maintaining this inclination during the remainder of the last pulling operation. This action is seen in the upper half of the plotted cam of 75 Fig. 6.

The cycle for a right shoe is seen on the lower half of the cam plot in Fig. 6, the rocking movement of the gripping head 200 terminating with the head and shoe reversely 80 inclined to press the inner side face of the downwardly moving last. A dotted line *c-c* extending centrally of the plotted cam groove, in conjunction with the line of the 85 groove indicates clearly the reverse swerving of the cam groove for right and left shoes in successive machine cycles.

The base of the indicator plate 214 extends through the yoke 210 and has an up- 90 standing flange 215 in a substantially parallel plane with the yoke and finger and to the rear of the finger. This flange bears suitable indicia such as "R" or "Right," and "L," or "Left," as suggested, the "R" or 95 "Right" being at the left side of the flange as viewed by the operator since the roll 217 in indicating position for "right" shoes rests in a portion of the cam groove 218 offset to the right of the central line of the cam 100 groove, as viewed by the operator, thereby causing the finger 212 to swing to the left. Obviously, the indication mark and direction of swing are reversed for "left" shoes.

The operation of the machine may be described in brief, as follows: The last and shoe are mounted on the carrier 144 and properly positioned between the grippers and the treadle 22 depressed. The cam wheel 36 begins to rotate, its initial movement causing 105 bell crank lever 64 to move the gripping members to engage and hold the shoe. During this period the rocking lever roll 209 is riding in the straight or dwell portion 220 of the cam groove 218 so that the gripping 110 head 200 remains stationary. At the end of this period the wiper cams begin to operate against the roll on bar 172 to move the carrier 144 and last downwardly through the 115 described connections. Coincidently with the downward movement of the carrier which acts to pull the last heel downwardly substantially to clear the edge of the shoe counter, the rocking bends 222 in the cam operate against the rocking lever roll 209 to 120 rock the gripping head 200 and the gripped shoe, stretching and loosening the shoe on the last and "easing" the heel portion of the last out of the shoe. When the heel of the last reaches the position, approximately, 125 130

where the last heel clears the edge of the shoe counter, the rocking motion of the shoe gripping head 200 will cease and the roll 209 will leave the rocking bends 222 and will 5 enter into the succeeding laterally offset straight portion 224 of the cam groove which will maintain the gripping head 200 transversely inclined (Figs. 4 and 5) while the last and carrier 144 are moved diagonally 10 downward out of the shoe as previously described, the inclination being maintained until the end of the machine cycle when a bend at the end of the offset portion 224 leads the roll 209 into the beginning of the 15 "dwell" section 220 of the next succeeding half of the cam groove, at which point rotation of cam wheel 36 ceases. The indicator roll 217 will, however, remain in the preceding laterally offset straight portion 224 20 of the groove and will incline the finger 212 to point to the shoe for which the inclination given the gripping head 200 by the next succeeding offset portion 224, is adapted, *i. e.*, the finger, at the end of an operation upon 25 a "left" shoe, will be inclined to point to the indication for a "right" shoe on the flange 215.

Having thus described my invention, what I claim as new, and desire to secure by

30 Letters Patent of the United States is:—

1. In a last pulling machine, in combination, means for holding a shoe, means for holding a last, mechanism for effecting relative movement of the shoe holding means 35 and last holding means to separate the shoe and last, and means operative to incline relatively the shoe and last transversely of the shoe and last and to maintain such relative inclination for a determinate period during 40 the relative separating movement of the shoe and last.

2. In a last pulling machine, in combination, means for holding a shoe, means for holding a last, mechanism for effecting relative movement of the shoe holding means 45 and last holding means to separate the shoe and last, and means operative during the separation of the shoe and last and substantially at that point in the separation when 50 the last heel clears the edge of the shoe counter, relatively to incline the shoe and last transversely of the shoe and last and to maintain such relative inclination during substantially the remainder of the period of 55 shoe and last separating movement.

3. In a last pulling machine, in combination, means for holding a shoe, means for holding a last, mechanism for effecting movement of the last holding means relatively to 60 the shoe holding means and in a direction to separate the last from the shoe, and means operative during the removal of the last to hold one side face of the shoe upper forcibly against a side face of the last to relieve 65 lateral pressure against the opposite side

face of the shoe upper as the last is removed therefrom.

4. In a last pulling machine, in combination, means for holding a shoe, means for holding a last, mechanism operative to move 70 the last holding means to pull the last from the shoe, and means automatically operative during the removal of the last from the shoe to move the shoe holding means and the shoe transversely relative to the last to press 75 one side face of the shoe against a side face of the last substantially to relieve the lateral pressure of the last against the opposite side face of the shoe upper as the last is removed therefrom. 80

5. In a last pulling machine, in combination, means for holding a shoe, means for holding a last, mechanism operative to move the last holding means to pull the last from the shoe, and means, automatically operative 85 during the removal of the last substantially when the last heel has been moved to clear the edge of the shoe counter, to move the shoe holding means to swing the shoe transversely relative to the last and against 90 one side face of the last substantially to reduce the lateral pressure of the last against the opposite side face of the shoe upper as the last is removed from the shoe.

6. In a last pulling machine in combination, means to hold a last in inverted position, means to engage and hold a shoe seated over the last, mechanism constructed and arranged to effect relative movement between the shoe holding means and the last holding 95 means to cause separation of the last and shoe, and means operative during the relative separating movement of the shoe and last, to effect relative transverse inclination 100 between the shoe and last substantially to 105 equalize lateral pressure of the last against the opposite sides of the shoe upper during relative separating movement of the shoe and last.

7. In a last pulling machine, in combination, shoe holding means, last holding means, mechanism operative to move the last holding means to pull the last from the shoe, and means operative during the removal of the last from the shoe automatically to 110 swing the shoe holding means to incline the bottom of the shoe from its normal plane and transversely relatively to the last to press and hold one side face of the shoe upper against a side face of the last during 115 the removal of the last from the shoe.

8. In a last pulling machine, in combination, means to engage and hold a shoe, said means being mounted for rocking movement, means to engage a last within the shoe, 120 mechanism operative to move the last engaging means to pull the last from the shoe, and means automatically operative at the point during the removal of the last when 125 the last heel bottom substantially clears the 130

edge of the shoe counter, to position and maintain the shoe engaging means and shoe inclined from its initial position and transversely of the last to hold one side face of the shoe pressed against the side face of the last during the continued separating movement of the last.

9. In a last pulling machine, means to hold an inverted shoe, means to engage an inverted last within the shoe, and mechanism constructed and arranged automatically to effect relative movement between the shoe holding and last engaging means in a direction to effect separation of a shoe and last and including means automatically operative in timed relation during such relative separating movement to effect relative transverse inclination of the shoe holding and last engaging means forcibly to engage and press in contact the side faces of a shoe upper and last at the inner side of the shoe.

10. In a last pulling machine, means to hold an inverted shoe, means to engage an inverted last within the shoe, and mechanism constructed and arranged automatically to move the last engaging means in a direction to pull the last from the shoe and including means automatically operative in timed relation to the separating movement of the last engaging means determinately to move the shoe holding means to swing a shoe transversely relatively to its last in the direction to press the side of the shoe at the inner side of the foot against the corresponding inner side face of the last and to maintain the shoe in such position during the remainder of the last separating movement.

11. In a last pulling machine, in combination, shoe holding means, last holding means, mechanism for effecting relative movement between the shoe and last holding means to separate the shoe and last, and means operative during the separation of the shoe and last, relatively and determinately to incline the shoe and last transversely of the shoe and last and at maintained angles of inclination reversed in alternation during successive cycles of the machine.

12. In a last pulling machine, in combination, shoe holding means, last holding means, mechanism effective to move the last holding means relative to the shoe holding means to remove the last from the shoe, and means operative during the removal of the last to move the shoe holding means to incline the shoe transversely of the last and to maintain it pressed against one side face of the last at angles of inclination reversed in alternation for right and left shoes during successive cycles of the machine.

13. In a last pulling machine, means to engage a last, means arranged for rocking movement, and constructed to grip a shoe on the last, and mechanism effective to move

the last engaging means to withdraw the last from within the shoe and including means operative during the removal of the last to rock the shoe gripping means to incline the shoe transversely of the last and to maintain it pressed against a side of the last at an angle of inclination automatically reversed in alternation during successive cycles of the machine.

14. In a last pulling machine, in combination, shoe holding means, last holding means, mechanism for effecting relative movement between the shoe holding means and the last holding means to separate the shoe and last, and means operative during the separation of the shoe relatively to incline the shoe and last transversely of the shoe and last and at maintained reverse angles of inclination for right and left shoes.

15. In a last pulling machine, in combination, shoe holding means mounted for rocking movement, last holding means, and mechanism for effecting movement of the last holding means to withdraw the last from within the shoe and including means operative in timed relation during the withdrawal of the last to rock the shoe holding means transversely to incline the shoe relatively to the last at maintained reverse angles of inclination for right and left shoes alternating in successive cycles of the machine.

16. In a last pulling machine, in combination, means to hold a shoe arranged for transverse rocking movement, means to engage a last within the shoe, and mechanism constructed and arranged automatically to move the last engaging means completely to remove a last from its shoe, and including means automatically operative during the withdrawal of the last and in timed relation to rock the shoe holding means determinately to position the shoe at maintained angles of inclination reversed in alternation for right and left shoes during successive cycles of the machine.

17. In a last pulling machine, in combination, means to engage and hold a last, means to grip a shoe on the last, mechanism effective to move the last holding means relatively to the shoe gripping means to remove a last from within a shoe, and means operative during the removal of the last to move the shoe gripping means in a direction to incline the shoe transversely and to maintain it pressed against one side face of a last for a right shoe and reversely to incline a shoe transversely and to maintain it pressed against the reverse side face of a last for a left shoe.

18. In a last pulling machine, in combination, shoe holding means, last holding means, mechanism for effecting relative movement between the shoe and last holding

- means to separate the shoe and last, means operative during the separation of the shoe and last and effective relatively to incline the shoe and last transversely of the shoe and last and at maintained angles of inclination reversed in alternation for right and left shoes during successive cycles of the machine, and means to indicate the conditioning of the machine for inclination for 5 right and left shoes.
19. In a last pulling machine, in combination, means to engage and hold a last, means to grip a shoe on the last, mechanism effective to move the last holding means relatively to the shoe gripping means to remove a last from a within a shoe, means operative during the removal of a last to move the shoe gripping means to incline the shoe transversely and to maintain it pressed 15 against one side face of a last for a right shoe and in the following machine cycle reversely to incline and maintain a shoe pressed against the reverse side face of a last for a left shoe, and means to indicate to 20 the operator the conditioning of the machine for inclination for right or left shoes in the particular machine cycle to be started.
20. In a last pulling machine, in combination, shoe holding means, last holding means, mechanism effective to move the last holding means relatively to the shoe holding means to remove the last from within the shoe, means operative during the removal of 25 the last to move the shoe holding means to incline the shoe transversely of the last and to maintain it pressed against a side face of the last at angles of inclination reversed in alternation for right and left shoes during 30 successive machine cycles, and means visually to indicate prior to the initiation of a machine cycle, the conditioning of the machine for inclination for right or left shoes.
21. In a last pulling machine, means to engage a last, means arranged for rocking movement and constructed to grip a shoe on a last, mechanism effective to move the last engaging means relative to the shoe gripping means to withdraw a last from within 35 a shoe, means operative during the removal of the last to rock the shoe gripping means to incline the shoe transversely of the last and to maintain it pressed against a side face of the last at angles of inclination automatically reversed in alternation for right and left shoes during successive cycles of the machine, and a movable indicator member automatically positioned in one cycle to indicate prior to the initiation of the next 40 succeeding cycle, the conditioning of the machine for inclination for right or left shoes.
22. In a last pulling machine, in combination, means for holding a last, means for engaging and gripping a shoe on the last, and mechanism constructed and arranged to 45 effect relative movement between the shoe and last in a direction to effect separation of the shoe and last, including means automatically operative in timed relation to stretch the shoe transversely on the last during such relative separating movement of the last and shoe.
23. In a last pulling machine, in combination, means for holding a last in inverted position, means for engaging and gripping a shoe seated over the last, and mechanism constructed and arranged to effect relative movement between the shoe and last in a direction to effect separation of the shoe and last, including means automatically operative in timed relation to move the shoe holding means transversely relative to the last to stretch the shoe on the last during the first 50 part of the relative separating movement between the shoe and last.
24. In a last pulling machine, in combination, means for holding a last in inverted position, means for engaging and gripping a shoe seated over the last, and mechanism constructed and arranged to effect relative movement between the shoe and last in a direction to effect separation of the shoe and last, including means automatically operative in timed relation to move the shoe holding means transversely relative to the last to stretch the shoe on the last during the first part of the relative separating movement between the shoe and last.
25. In a last pulling machine, in combination, means for holding a last in inverted position, means to engage and grip a shoe seated over the last and arranged for transverse rocking movement, and mechanism constructed and arranged to move the last holding means relative to the shoe and in a direction to withdraw the last from within the shoe, including means automatically operative in timed relation to rock the shoe gripping means and shoe transversely of the last to stretch the shoe on the last during the first part of the separating movement of the last.
26. In a last pulling machine, in combination, means for holding a last in inverted position, means mounted for rocking movement and arranged to engage and grip a shoe seated over the last, and mechanism constructed and arranged to move the last holding means relatively to the shoe and in a direction to withdraw the last from within the shoe including means automatically operative in timed relation to rock the shoe gripping means and shoe transversely of the last to stretch the shoe on the last during the first part of the separating movement of the last, and effective subsequently.

determinately to position and maintain the shoe against further transverse rocking movement.

27. In a last pulling machine, in combination, a shoe engaging means mounted for rocking movement, means to engage and hold an inverted last, said means being positioned in a plane below the shoe engaging means and arranged manually to be moved to 10 position a last with its shoe in coöperative relation to the shoe engaging means, and mechanism operative automatically to operate said shoe engaging means to engage and hold the shoe and operative automatically 15 relatively to move the shoe holding and last holding means in a direction to remove the last from within the shoe, and including means operative in timed relation to rock the shoe holding means transversely 20 of the last during the initial stages of shoe and last separation.

28. In a last pulling machine, in combination, a shoe engaging means mounted for rocking movement, means to engage and 25 hold a last, said means being positioned in a plane below the shoe engaging means and arranged manually to be moved to position a last with its shoe in coöperative relation to the shoe engaging means, and mechanism 30 operative automatically to operate said shoe engaging means to engage and hold the shoe and operative automatically to move the last holding means in a direction to remove the last from within the shoe, and including 35 means to rock the shoe holding means transversely of the last during the initial stages of shoe and last separation, and thence to position and maintain the shoe for the remainder of the separating operation 40 terminately inclined from the plane in which it was initially positioned.

29. In a last pulling machine, in combination, a shoe holding means, last holding means, mechanism constructed and arranged 45 to effect relative movement between the last holding means and the shoe holding means to separate the shoe and last, and means arranged automatically to effect relative transverse rocking movement between the 50 shoe and last during the initial stage of separation to stretch and loosen the shoe on the last, said means being subsequently effective relatively to incline the shoe and last transversely of the shoe and last and to 55 maintain such relative inclination during the remainder of the separating movement.

30. In a last pulling machine, in combination, shoe holding means, last holding means, mechanism constructed and arranged 60 automatically to move the last holding means relatively to the shoe holding means to effect separation of a last from a shoe, and mechanism automatically operating in timed relation to rock a shoe transversely

on its last prior to the point substantially 65 when the bottom of the last heel clears the edge of the shoe counter and subsequently operative transversely to incline and to maintain a shoe at a determinate angle to its initial plane to press the inner side face of a shoe against the inner side face of a last. 70

31. In a last pulling machine, in combination, shoe holding means, last holding means, and mechanism constructed and arranged automatically to effect relative movement between the last holding means and the shoe holding means to effect separation of the last and shoe including means automatically operative in timed relation during the initial stage of separation relatively to move the 80 shoe and last holding means transversely of the shoe and last to stretch and loosen the shoe on the last and subsequently operative relatively to incline and maintain the shoe and last inclined transversely of the shoe and last in a direction to press the inner side of a shoe against the inner side face of a last during the remainder of the relative separating movement of the shoe and last. 85

32. In a last pulling machine, in combination, shoe gripping means mounted for rocking movement, means to engage a last seated within a gripped shoe, and mechanism operative to move the last engaging means to withdraw a last from within a shoe and including means automatically operative during the initial stage of the last withdrawal to rock the shoe gripping means and shoe transversely relative to the last to stretch and loosen the shoe on the last and subsequently to arrest rocking movement of the shoe gripping means with the shoe determinately inclined transversely relative to the last and maintained so inclined to press one side of the shoe against a side face of the last as the latter is withdrawn from the shoe. 100

33. In a last pulling machine, in combination, shoe holding means mounted for transverse rocking movement, means to engage a last within the shoe, and mechanism constructed and arranged automatically to move the last engaging means to effect separation of the last from the shoe, and including means operative in timed relation automatically to rock the shoe holding means and shoe transversely of the last during the initial stage of last separation and operative subsequently to swing the shoe holding 115 means transversely relatively to the last to incline the shoe from its initial plane and to maintain the shoe so inclined during the remainder of the last separating movement, the angle of inclination being arranged to 120 press the inner side face of the shoe against the inner side face of the last to transfer, at least in part, the lateral strain of the 125

last against the shoe upper from the outer side face of the shoe to the inner side face of the shoe.

34. In a last pulling machine, in combination, means for holding a last, means for gripping a shoe on a last, and mechanism constructed and arranged to effect relative movement between the shoe and last holding means to separate the shoe and last, 10 mechanism operative during the initial stages of shoe and last separation relatively to rock the last holding and shoe gripping means transversely of the shoe and last to stretch and loosen the shoe on the last, and 15 including means subsequently operable relatively to incline the shoe and last transversely of the shoe and last at a maintained angle of inclination reversed in alternation during successive cycles of the machine.
- 20 35. In a last pulling machine, in combination, shoe holding means mounted for rocking movement, last holding means, and mechanism effective to move the last holding means relative to the shoe holding means 25 to remove the last from the shoe including means operative in timed relation during the initial stage of last removal to rock the shoe holding means transversely relative to the last to stretch and loosen the shoe on the 30 last and operative to arrest rocking movement of the shoe holding means with the shoe inclined relative to and transversely of the last to press the inner side of the shoe against the inner side face of the last and to 35 maintain the shoe pressed against the last at angles of inclination reversed in alternation for the inner side faces of right and left lasts during successive cycles of the machine.
- 40 36. In a last pulling machine, in combination, shoe holding means mounted for rocking movement, last holding means, a power operated cam wheel with operating connections to said last holding means auto-

matically to move said last holding means 45 to remove the last from the shoe and with operating connections to said shoe holding means automatically to rock said means in timed relation during the initial stage of last removal and subsequently to arrest 50 rocking movement of the shoe holding means to position and maintain the shoe during the remainder of the cycle inclined transversely relative to the last with the inside of the shoe pressed against the inner side 55 face of the last, and means automatically to reverse the maintained angle of inclination in alternation during successive machine cycles alternately to press the inner sides of right and left shoes against the oppositely located inner side faces of right and left lasts.

37. In a last pulling machine, in combination, means to engage and hold a last, means mounted for rocking movement arranged to grip a shoe on the last, and mechanism effective automatically to move the last holding means relatively to the shoe gripping means to remove a last from within a shoe and including means operative in timed relation 65 during the initial stage of last removal to rock the shoe gripping means and shoe transversely of the last to stretch and loosen the shoe on the last and subsequently operable 70 to arrest said rocking movement determinately to incline the shoe transversely of and to maintain it pressed against one side face of a last for a right shoe and operable in the following machine cycle reversely to incline and maintain a shoe pressed against 75 the reverse side face of a last for a left shoe, with means to indicate prior to the initiation of a cycle the conditioning of the machine for inclination for right or left shoes and lasts in the particular machine cycle. 80

In testimony whereof I have signed my name to this specification.

BENJAMIN F. MAYO.
